DESIGN FOR A DISPLAY STAND

Rudolph Redlich, Chicago, Ill., assignor to Lacy Products Corp., Chicago, Ill., a corporation of Illinois

Application November 30, 1938, Serial No. 81,483

Term of patent 3½ years

To all whom it may concern:

Be it known that I, Rudolph Redlich, a citizen of the United States, residing at Chicago, Cook County, Illinois, have invented a new, original, and ornamental Design for a Display Stand, of which the following is a specification, reference being had to the accompanying drawing, forming a part thereof.

I claim:

The ornamental design for a display stand, as shown.

RUDOLPH REDLICH.
